UNITED STATES PATENT OFFICE.

RALPH C. BRONSON, OF CHICAGO, ILLINOIS, ASSIGNOR OF ONE-HALF TO WILLIAM J. KRUEGER, OF CHICAGO, ILLINOIS.

FUSE-PLUG.

1,071,871.

Specification of Letters Patent.

Patented Sept. 2, 1913.

Application filed May 9, 1912. Serial No. 696,104.

To all whom it may concern:

Be it known that I, RALPH C. BRONSON, a citizen of the United States, and a resident of Chicago, in the county of Cook and State of Illinois, have invented a new and useful 5 Fuse-Plug, of which the following is a specification.

My invention relates to that variety of fuse plug which it is the present general 10 practice to employ in incandescent electric lighting circuits to prevent any ignorant or accidental overloading thereof.

As is well known, such construction comprises a socket with the bottom and side of 15 which the circuit is connected, and into which screws the fuse plug comprising a suitable insulating member, means for contacting the bottom and side terminals of the socket and a connecting member between the 20 contracting means of readily fusible metal which will fuse and break the circuit should it become overloaded.

The object of my invention is to provide such a fuse plug in a simple and economical 25 construction which will have a number of fuses which may be successively brought into operation instead of having to replace the entire plug when a fuse is blown.

I attain the above object by means of the 30 structure illustrated in the accompanying drawing, in which:—

Figure 1 is a top plan of my new fuse plug; Fig. 2 is a view similar to that of Fig. 1 with the cover retaining means and 35 cover removed; Fig. 3 is a bottom plan; Fig. 4 is an elevation; and Fig. 5 is a vertical section on lines 5—5 of Figs. 1 and 2.

Similar reference numerals refer to similar parts throughout the several views.

40 The plug comprises a piece of suitable insulating material such as porcelain or vulcanite of a cylindrical form formed with the reduced portion, 1, to extend into the socket, and the enlarged end portion, 2. The 45 end of the portion, 1, is suitably recessed at 3, to receive a disk or plate, 4, to which the fuse elements are soldered. It is also centrally recessed at 5 to receive the screw, 6, and nut, 7, which secures an additional 50 metallic washer, 8, against the disk or plate, 4, so as to hold the disk, 4, firmly in position and also insure a good contacting portion for the bottom terminal of the socket (not shown). The upper portion of the 55 central recess, 5, is filled with a suitable sealing and insulating material, 9, when the

bolt 6, and nut 7, are in position. The face of the enlarged end, 2, is recessed to form the rim, 10, and annular shoulder, 11, and below the shoulder are formed a plurality of 60 segmental chambers 12. Through the bottoms of the chambers, 12, are provided round openings 13, the continuations of which form the semi-circular channels 14, in the portion, 1, of the plug clearly shown in Figs. 65 3 and 4.

Secured to the bottoms of the chambers, 12, by means of screws, 15, are plates, 16, having bored ends, 17, the bored portions of 70 which register with the openings 13. Channels, 18, are provided which extend from the bottom of each chamber 12, near the plate, 16, to the edge of the disk or plate, 4, and through these channels extend the fuse 75 wires, 19, the ends of which are soldered respectively to the disk 4 and to the respective plates 16.

About the outside of the reduced portion, 1, of the plug is a metallic cylinder, 20, in which has been spun a thread, 21, so as to 80 screw into the socket (not shown) and contact with the side terminal of said socket. To the upper edge of the cylinder, 20, is secured the stud, 22, which is proportioned to lie partially in a semi-circular channel, 14, 85 and extend upwardly into the opening, 13, in the bottom of the chamber 12. The stud, 22, is bored and threaded to receive a screw, 23, passing down through the bored ends, 17, of the plate, 16, thereby performing the 90 double purpose of holding the cylinder, 20, in position and making connection between it and the fuse, 19, through the plates, 16. Within the rim, 10, and upon the annular shoulder, 11, is a cover disk, 24, of mica or 95 other suitable material held in position by the spring clip, 25, the ends of which extend through holes bored in the rim for that purpose. But one screw, 23, being employed at a time it will be seen that connection will 100 be made through the plug by only one fuse wire at a time, and when the fuse in use is blown another fuse may be easily brought into use by removing the cover, 24, removing the screw 23, which will permit the withdrawal of the insulating block from the cylinder, 20. The insulating block is then turned so as to cause the stud, 22, to project into the opening, 13, of a different chamber, the screw 23 is again inserted and a new 110 fuse is in circuit.

Having described my invention what I

claim as new and desire to secure by Letters Patent, is:—

1. A fuse plug comprising a substantially cylindrical insulating member having recessed compartments in one end thereof, and separate channels running respectively from each of said compartments to the opposite end of said insulating member and to the outer side thereof, a contact plate secured to the end of said insulating member opposite said compartments, fuse wires running from said plate through some of said channels to said compartments, a contact cylinder surrounding said insulating member, and a screw extending through one of the channels leading from said compartment to the side of said insulating member to secure said cylinder in place and make connections between said cylinder and said fuses.
- 20 2. A fuse plug comprising a piece of insulating material, an end contact plate thereon, a threaded cylindrical contact member adapted to slip over the sides thereof, a screw for securing said cylinder to said insulating material at different points, and

fuse wires running through said insulating material from said contact plate to the different points for the securing of said cylinder.

3. A fuse-plug comprising an insulating member having a plurality of channels extending therethrough, and a plurality of contact plates secured to one end of said member and a single contact plate secured to the opposite end, fuse-wires extending through said channels and connecting said single contact member with the contact plates first mentioned, respectively, a contact member surrounding said insulating member, and means connecting said contact member with one of the plural contact plates first mentioned, and adapted to be connected with each of the other plural contact plates.

In testimony whereof I affix my signature in the presence of two witnesses.

RALPH C. BRONSON.
